UNITED STATES PATENT OFFICE.

JAMES SEALEY, OF CHASE, MICHIGAN.

LUMBER-BINDER.

SPECIFICATION forming part of Letters Patent No. 291,786, dated January 8, 1884.

Application filed September 26, 1883. (No model.)

To all whom it may concern:

Be it known that I, JAMES SEALEY, a citizen of the United States, residing at Chase, in the county of Lake and State of Michigan, 5 have invented certain new and useful Improvements in Log and Lumber Binders, of which the following is a specification, reference had therein to the accompanying drawings.

This invention has relation to improvements 10 in devices for binding logs and lumber upon wagons, cars, trucks, sleighs, and the like; and it consists in the construction and novel arrangement of parts as will be hereinafter more fully set forth, and particularly pointed 15 out in the claim appended.

In the accompanying drawings, to which letters of reference are made, Figure 1 is a representation of a side elevation of my invention, showing the same applied to a bundle of logs 20 ready to be bound; and Fig. 2 is a view of the same, showing it applied to the logs in a bound position.

Referring by letter to the drawings, A indicates a lever, which is provided at one end 25 with a handle, a, and is bent near its opposite end, as at b, the upper edge, c, of which is convex, and the under portion, d, concave. About midway this curved or bent portion, to one side of the lever, is pivotally connected a 30 straight arm, B, in the lower end of which is an eye, d', carrying a link, e. To the extreme end of this curved portion of the lever is also pivotally connected an arm, C. This latter arm is connected to the side of the lever opposite to that of the straight arm B, and is 35 in outline of a similar form to the curved portion b of the said lever. The whole device is preferably constructed of a flat bar of iron or steel, and the arm C, at its lower or free 40 end, is bent over nearly upon itself, as shown, forming a groove, g, to receive one edge of the

lever A, which grooved portion forms a bearing for the lever when the device is in a bound position. From this bent portion extends a lateral offset, n, which is provided with an 45 eye and chain-link, to receive one end of the binding-chain, the opposite end being secured in the link of the straight arm B, as shown.

From the foregoing description it will be seen that the main object of my invention is 50 to get a double eccentric movement. Thus, when the logs or lumber is placed upon a wagon or the like and the chain passed around both the wagon-body and the logs, connecting its ends to the links in the pivoted arms, the 55 device will assume the position shown in Fig. 1 of the drawings; but by the operator bringing the lever A toward him and downward until the portion b is brought to bear in the groove of the arm C, the chain will be drawn 60 up and the device assume the position shown in Fig. 2.

Having thus described my invention, what I claim as new, and desire to secure by Letters Patent, is—

In a log and lumber binder, the combination, with the lever A, having the concavo-convex portion b, of the arm C, of a similar contour and shape, provided with the groove g, to receive the upper edge of the lever, and 70 a short perforated arm to receive a chain-link, the straight arm B, pivoted at its upper end to the said concavo-convex portion of the lever A, and provided at the opposite end with an eye to receive a chain-link, and the binding-chain, substantially as specified.

In testimony whereof I affix my signature in presence of two witnesses.

JAMES SEALEY.
